P. BROWN

IGNITION APPARATUS

Filed Oct. 12, 1925

UNITED STATES PATENT OFFICE.

PHELPS BROWN, OF SPRINGFIELD, MASSACHUSETTS.

IGNITION APPARATUS.

Application filed October 12, 1925. Serial No. 62,057.

This invention relates to improvements in ignition apparatus of the so-called reciprocating armature type in which ignition currents are intermittently generated.

5 In magnetos of this type, as heretofore constructed, the ignition spark is produced entirely on one stroke of the reciprocating armature. The other stroke of the armature accomplishes no useful work. The armature on its idle stroke necessarily produces a change of flux in the magnetic circuit but such change has not been utilized. Such change of flux on the idle stroke of the armature sometimes gives rise to a so-called 10 "upthrow" spark. It always gives rise to a change of flux which might be utilized for the production of an electromotive force. The effort, heretofore, has been to stifle the upthrow spark and prevent it from occurring. That is, the upthrow spark has heretofore been considered as a nuisance and effort has been made to keep the electromotive force induced on the upthrow stroke of the armature at as low a value as possible, as 15 by controlling the rate of change of flux and in other ways.

This invention is concerned with, and has for an object, the turning of what has heretofore been considered as a nuisance into useful work and, more than that, it is concerned broadly with the utilization, to as full degree as may be possible in each case, of the hitherto idle stroke of the armature. The necessity for keeping the electromotive 20 forces generated on the upthrow of the armature at low values no longer exists because since this electromotive force can be made to do useful work, the larger it is the better.

25 The invention is likewise concerned with the adaptation of ignition apparatus of the reciprocating armature type to high speed, multi-cylinder engine work. For such work the apparatus must produce a great many more sparks per minute than has heretofore been necessary. With one unit, the time available for a cycle of armature operation, including getting the armature on and off its poles and a dwell of the armature on its 30 poles, is reduced to exceedingly small limits. The one unit would have to be worked exceedingly fast and hard. Accordingly, it is an object of the invention to provide an ignition apparatus of the reciprocating armature type involving two generating units, 35 between which the work may be divided so

that each need not be worked so hard and fast, and to make each unit during its hitherto idle stroke, help the other unit in a manner broadly analogous to that in which 40 the weight of the descending car of a funicular railway aids the ascending car.

In carrying out this object the reciprocable armature flux changing means cooperates with the two magnetic circuits of the 45 two units to increase the reluctance of each alternately so that when the reluctance of one is substantially at a minimum that of the other is substantially at a maximum. Coupled with this arrangement is a control, 50 including normally short circuited choke windings, associated with the magnetic circuits, and means for opening the circuits of said choke windings, whereby the electromotive forces generated in each unit are 55 caused to occur intermittently and substantially instantaneous. Such control is particularly characterized by timing the electromotive force generated in one unit, when its magnetic circuit is substantially open, 60 with that generated, when the other magnetic circuit is substantially closed, and the two units are so connected electrically that the two electromotive forces simultaneously 65 induced in each unit during each stroke of the reciprocable armature flux changing means are merged, whereby each unit is co-ordinated with and contributes to the work of the other.

70 Other objects and advantages will appear 90 in the following description and will be pointed out in the appended claims.

The invention will be disclosed with reference to the one illustrative embodiment of it shown in the accompanying drawings, 95 in which:—

Fig. 1 is a front elevational view of an ignition apparatus embodying my invention;

Fig. 2 is an end elevational view thereof;

Fig. 3 is a top plan view;

Fig. 4 is a sectional plan view taken on the line 4—4 of Fig. 1;

Fig. 5 is a fragmentary cross sectional view taken on the line 5—5 of Fig. 4;

Fig. 6 is a diagrammatical view illustrating 105 of the electrical circuits of the apparatus; and

Fig. 7 is a perspective view showing parts of the armature and its actuating mechanism in dissociated relation.

110 Referring to these drawings; the ignition apparatus, disclosed therein, involves two

units which, however, are connected to work in cooperative relation, each assisting and contributing to the work performed by the other. The two units, as shown, are supported from a common frame, driven from a common drive shaft and utilize a common source of magnetic flux. The units, functionally considered, are nevertheless, separate and distinct. These two units being exactly alike, one only will be described in detail and the corresponding parts of the other unit will be designated by the same reference numerals primed.

Each unit has a magnetic circuit including two cores 10, the upper ends of which are connected to a suitable source of magnetic flux, such as the permanent bar magnets 11, and the lower ends of which constitute magnetic poles. Such circuit also includes flux changing means, of the reciprocating type, such as an armature 12, which is mounted for movement toward and preferably into contact with said poles and subsequently away from the same. As shown, each unit has a separate armature but, while this is desirable and preferred, it is by no means essential in so far as the broader aspects of the invention are concerned. The important thing is that the flux changing means, whether consisting of two armatures or otherwise, is arranged to first increase the reluctance of one magnetic circuit and then the other. The arrangement is such that, when one magnetic circuit is substantially at a maximum, the reluctance of the other is substantially at a minimum. In the particular embodiment shown, as one armature is just leaving its poles the other armature is just about to contact with its poles. This exact time relation is not essential for all purposes and may be varied within reasonable limits, as desired.

Each unit also includes a generating winding, comprising two coils 13, mounted one on each core 10, and suitably connected to function as one winding. As shown in Fig. 6, these coils are connected in series so that the electromotive forces generated in each are added, although they may be otherwise connected, if desired. The generating winding of each unit is electrically connected to the generating winding of the other unit so that the electromotive forces produced in each are merged in a common ignition circuit. As shown in Fig. 6, the winding, including the coils 13, is connected in series by a wire 14 with the winding, including the coils 13', in such a fashion that the electromotive forces, which are simultaneously produced in opposite directions in each, are caused to be added and caused to flow all in the same direction in a common ignition circuit. Such circuit may include a distributor D electrically connected by a wire 15 to one terminal of the connected generating windings, which

distributor periodically and successively connects the ignition circuit to two spark plugs S. One terminal of these plugs being grounded, the other terminal of the connected generating windings is likewise grounded, as indicated at 16.

The manner in which the generated electromotive forces are utilized is not important and that shown is merely illustrative. So also, the manner, in which the two generating windings are connected, is not necessarily essential so far as all features of the invention are concerned although it is important and preferred. Any other means for connecting the two generating windings so that the generated electromotive forces are merged in a common ignition circuit may be used, if desired, in so far as the broader features of the invention are concerned.

Associated with the magnetic circuit of each unit is a choke winding, herein shown as comprising two coils 17, mounted one on each core 10 and between the latter and the generating coil 13. These coils may be connected in any suitable way to function as one choke winding. As shown in Fig. 6, they are connected in electrical series by a wire 18. The purpose of this choke winding, which as usual is normally short circuited, is to restrain substantial flux change in the magnetic circuit until the reciprocating armature flux changing means has reached a predetermined position most favorable for the production of an electromotive force, at which time the choke winding circuit is opened to release the magnetic circuit for a rapid flux change, whereupon an electromotive force is generated in coils 13. The electromotive force generated is therefore intermittent and practically instantaneous. It occurs at one point only in each stroke of the armature 12. It is therefore essential that the electromotive force induced in one winding be nicely controlled and timed so as to occur simultaneously with the electromotive force induced in the other winding.

As a control, I provide the choke winding described together with interrupter mechanism for opening and closing the circuit thereof. Such means normally causes the choke winding to be in a closed circuit and thus in flux change restraining condition. However, when the armature 12 on its down stroke has established an air gap of predetermined degree in one magnetic circuit, the interrupter mechanism opens the choke winding therefor and allows the flux to rapidly die out of such circuit to induce an electromotive force in one generating winding, say for example, that comprising the coils 13. At the same time, the interrupter mechanism opens the circuit of the choke winding associated with the other magnetic circuit, which has just been closed by the seating of the armature 12' on its poles. In consequence,

flux rapidly builds up in this magnetic circuit, resulting in the generation of an electromotive force in the winding, comprising the coils 13'. Thus, two electromotive forces 5 are simultaneously produced, one by a decrease of flux and one by an increase of flux and these two electromotive forces are merged in a common ignition circuit so that the one generating unit assists the other. As 10 armature 12 nears its poles, the interrupter mechanism will close the circuits of both choke windings. Armature 12' will move away from its poles at very nearly the same time that armature 12 engages its poles. 15 When armature 12', in its downward flight, has created a sufficient air gap in the magnetic circuit, of which it is a part, the interrupter mechanism will again simultaneously open the circuit of both choke windings and 20 two electromotive forces will be simultaneously induced in the two generating windings but in opposite directions to those heretofore described.

While any suitable means for effecting the 25 functions above attributed to the interrupter mechanism, may be used I prefer for simplicity and convenience to use the two separate interrupters connected together in electrical series and to operate one by the armature 30 12 and the other by the armature 12'. These interrupters may be of any type suitable for the purpose and the particular type shown is merely illustrative of one type which I have found suitable. One only of 35 these interrupters will be described, the other being designated by the same reference numerals primed. The interrupter comprises relatively fixed and movable breaker points 19 and 20, respectively,—the former being 40 supported by and insulated from a sleeve-like casing 21 fixed to the frame of the machine. The movable point 20 is carried by a plunger 22, guided in casing 21 and extending below the latter and loosely through an 45 opening in a bracket 23, secured to armature 12. At its lower end the plunger 22 carries a head 24 and a spring 25 acts on the latter to normally hold the points 19 and 20 in contact. The head 24 is spaced from the 50 bracket 23 and will not be engaged thereby until armature 12 has moved away from its poles a substantial distance and therefore not until an air gap of predetermined degree has been established in the magnetic circuit. 55 It will also be seen that spring 25 will be allowed, on the upthrow of the armature, to move point 20 into engagement with point 19 before armature 12 is seated on its poles. Thus, these points engage before armature 60 12' has moved far enough away from its poles to separate the breaker points 19' and 20'. Therefore, the two interrupters operate alternately and, being connected in series in the choke winding circuits, the separation 65 of either pair of breaker points will open

the choke winding circuit. The same result could, of course, be obtained by making each armature operate the same interrupter but at different times.

The choke winding circuits are shown in 70 Fig. 6. Each movable point 20, being connected with the metallic frame of the machine, is grounded. Therefore, the two movable points are electrically connected and for convenience such connection has 75 been indicated in Fig. 6 by the dotted line 26. Each of the fixed points 19 and 19' are connected by wires 27 with the terminals of the choke winding, comprising the coils 17', and they are also each connected by wires 80 28 with the terminals of the choke winding, comprising the coils 17. Each choke winding is therefore short circuited at the proper times by the same means, which comprises the engaged points 19 and 20, the ground 85 connection 26 and the engaged points 19' and 20'. The two choke windings are thus arranged in multiple but this arrangement while preferred, is not essential to all features of the invention. The breaker points, 90 according to usual practice, are bridged by a condenser 29 and one condenser, arranged as shown in Fig. 6, will serve for both sets of breaker points. From the foregoing it will be clear that when either set of breaker 95 points open, both choke windings will be open circuited. Also, it will be clear that these choke winding circuits will be opened twice during each cycle of operation of the armature, once during the down stroke and once shortly after the end of the upstroke while the armature is seated on its poles. 100

Referring now to the details of the exemplary apparatus shown in the drawings, the cores 10 are built up from soft iron 105 laminations in the usual way. They are laterally spaced and vertically disposed. Behind the cores 10 in parallel but spaced relation are the cores 10'. The cores 10, near their lower ends, are received in recesses in a cross bar 30 (Figs. 2 and 3) and secured thereto by screws 31 (Fig. 1). At their upper ends the cores 10 are extended above the coils 13 and are fashioned with recesses to receive between them the magnets 11, herein shown as a vertical stack of four. The magnets are frictionally held in place in the recesses by shims 32. The cores 10' are similarly arranged to receive a second 110 group of magnets 11'. Between the upper extensions of each pair of cores 10 and 10' are placed other sets of laminations 33 which receive between them a third stack of magnets 11''. The laminations 33 are similar 115 to the core laminations except that they lack the depending core forming parts. All the laminations are clamped together just above coils 13 by bolts 34. The cores 10 are tied together above coils 13 by a cross bar 35 and this bar, together with the correspond- 120

ing bar 35' is held in place by the bolts 34.

The cross bars 30 and 30', which are disposed in spaced parallel relation, extend between, and are secured at their ends by screws 36 to a pair of upstanding brackets 37, which in turn are mounted on a common bed plate 38. Rotatably mounted in brackets 37 and extending therebetween is a drive shaft 39 serving to operate both armatures in properly timed relation. Below and parallel with shaft 39 is a rod 40, mounted at its ends in brackets 37 and extending therebetween. Shaft 39 and rod 40 are both disposed in the same vertical plane and in a plane which lies between the cores 10 and 10'. Rod 40 serves as a common pivotal support for the two armatures 12 and 12'. Armature 12 has on its inner face a bracket 41, held thereto by bolts 42, which also serve to hold the described bracket 23 in place as well as to clamp the laminations of the armature together. The bracket 41 and the corresponding bracket 41' have hubs which are mounted to turn on rod 40 so that the armatures 12 and 12' are supported for independent swinging movement. These hubs abut at their inner ends, as shown in Fig. 4, and at their outer ends are held spaced from the brackets 37 by collars 43.

The armatures 12 and 12' may be moved to and from their poles by any suitable mechanism and that shown herein is purely exemplary and forms in itself no part of the present invention. By preference and for the particular use above described, I prefer to operate the armature according to the general manner set forth in U. S. Letters Patent No. 1,517,948, granted December 2, 1924. That is, the armature when the engine is started or when running at low speed, may be removed from its poles by an inelastic transmission from the drive shaft 39 and then driven in its flight away from its poles by the expansion of previously stressed elastic means and when the engine is running at normal speeds the armature may be driven entirely by the inelastic transmission. Since these methods of operating the armature together with means for changing from one method to the other are fully set forth in said patent, it is unnecessary to describe them in full detail herein.

As shown in the drawings, the armature bracket 41 is provided with two lugs 44 and 45 arranged in longitudinally spaced relation. Two arms 46 and 47, disposed vertically one above the other, are mounted to turn upon a common pivot shaft 48 which is fixed to a bracket 49 secured to cross bar 30. These arms are interfitted (Fig. 1) so as to move together longitudinally on pivot 48. These arms can swing independently and a spring (not shown) tends to force them apart. The upper arm 46 has a lug 50 overlying lug 44 but capable of being disengaged

therewith, when the arms are longitudinally shifted. The lower arm 47 always overlies lug 45 and drives the armature through the elastic means when lugs 50 and 44 are disengaged. The upper arm 46 is acted upon by a cam 51 on drive shaft 39 and can operate the armature directly through lugs 40 and 44 or indirectly through arm 47 and lug 45. The means for shifting the arms 46 and 47 to change from one form of drive to the other is not shown herein.

The cams 51 are fixed to drive shaft 39 and are angularly spaced 180 degrees apart. Each consists of a dwell portion, which is a little less than 180 degrees in extent, and similar rise and fall portions, which make up between them the balance of the periphery of the cam. The rise and fall portions are arcs of circles equal in radius to the radius of the hole in a collar 52, which loosely encompasses the cam and through which the cam acts on the upper arm 46. Cam 51, through lever 46, pushes the armature down away from its poles, at first relatively gradually and then more rapidly. A spring 53 tends to move the armature upwardly, when permitted by cam 51, and the latter permits the armature to rise at first relatively fast and finally more slowly as the armature nears its poles. The particular armature movements described may, obviously, be varied as desired. This upward movement with diminishing speed as the armature nears its poles is used to secure as quiet a seating of the armature on its poles as possible and, taken in conjunction with the choke winding, which is short circuited at the time to diminish the magnetic pull on the armature, accomplishes its purpose. If reduction of noise is not desired the speed of the armature on its upthrow stroke may be increased as desired.

The operation will largely appear from the foregoing description and need be but summarized here. Each unit of the ignition apparatus on the downthrow of its armature produces an electromotive force in the former way and such electromotive forces are generated every half revolution of the drive shaft 39 which for four cycle, four cylinder engine work may be driven at crankshaft speed. The work accomplished by the downthrow of one armature is, however, aided by the upthrow of the other armature. Hence the analogy to the funicular railway. The upthrow and the downthrow movements are coordinated and they cooperate and contribute each to the other. The change of condition, brought about in the magnetic circuit of one unit by the upthrow of the armature, is utilized to produce an electromotive force, which is merged with the electromotive force produced in the other unit in the ordinary way by the downthrow of the armature. With the aid of the control, such as the

choke windings and the interrupter mechanisms, the electromotive force, generated in one unit by the change in condition of the magnetic circuit caused by the upthrow of

5 the armature, is caused to occur simultaneously with the electromotive force generated in the usual way by the downthrow of the armature.

The two units thus divide the work between them, each helping the other during that stroke of the armature which has heretofore been idle. More sparks per minute can be produced without working the generating units as hard or fast as would be necessary if only one unit were used. Each armature can dwell on its poles for nearly half a revolution of the drive shaft, whereas if one armature were used and operated twice each revolution by two cams, then only one half a revolution would be available for getting the armature on and off its poles and for getting the dwell of the armature on its poles. With the present arrangement much more time is available to manipulate the armatures, which is of great importance here where a magneto, of a type formerly used for relatively slow speed work, is adapted for work at very much higher speeds. Each unit also aids the other in another sense in that the magnetic circuit of one helps to secure a more rapid flux change in the other. That is, when one magnetic circuit is fully broken and the breaker points open to release the circuit for a flux change, the other magnetic circuit, which is then closed, shunts the flux from the first and causes it to die out much more rapidly than it otherwise would.

In the particular embodiment of the invention illustrated, each armature is moved into contact with its poles while the choke winding of its magnetic circuit is short circuited. This arrangement, while not at all essential to the broader features of the invention, is, as has been above pointed out, desirable when it is desired to seat the armature as quietly as possible on its poles. This arrangement is a feature of U. S. Letters Patent No. 1,488,975, granted to me on April 1, 1924. As brought out in said patent, it is desirable when this arrangement is used, particularly in high speed magnetos, to provide for an extra opening of the breaker points after the armature has been seated on its poles in order to allow the flux to build up rapidly. This extra opening and closing of the breaker points has been called a "flux valve" in the trade. It is a feature of this invention that the usual opening and closing of the breaker points, effected when one magnetic circuit is broken, serves also as the flux valve for the other magnetic circuit after it has been closed. The one interrupter thus performs two functions. The so-called flux valve action,—that is the open-

ing of the choke winding circuit after the armature has been seated on its poles,—gives rise to the upthrow spark, which as above pointed out, was formerly undesirable. Various methods have, heretofore, been used to kill this spark. This invention incidentally affords a useful way of preventing the upthrow spark from doing damage by merging it with the downthrow spark.

However, with the present arrangement there is no necessity for limiting the so-called upthrow electromotive force, as has heretofore been desirable. Such electromotive force is extremely useful when, as here, it can be merged with the downthrow electromotive force and made to do useful work. Accordingly, such upthrow electromotive force can, and desirably is, made as large as possible compatible with the particular conditions of each installation.

The essential feature of this invention consists in securing a cooperative action between two generating units whereby one is made to help the other as above set forth. The details, therefore, are not important and may be varied in many ways. So also, the particular arrangement and disposition of the parts of the magnetic circuit may be varied as it is only necessary that one part thereof move toward and away from another part in general reciprocating fashion. The term "armature" as used herein is intended to mean the moving element of the magnetic circuit and is not used in any limited or strict technical sense. The term "poles" and "magnetic poles", as used herein, is intended to mean those parts of the magnetic circuit with which the moving element cooperates and is not to be construed in a limited or strict technical sense.

The invention has been disclosed herein, in an embodiment at present preferred, for illustrative purposes, but the scope of the invention is defined by the appended claims rather than by the foregoing description.

What I claim is:

1. Ignition apparatus, comprising, two generating units including reciprocable armature flux changing means and means for operating the latter, each unit arranged for the production of an intermittent electromotive force on each stroke of said reciprocable means, controlling means arranged to time the production of the electromotive forces in said units one with the other so that the two intermittent electromotive forces produced in the two units on each stroke of said reciprocable means occur simultaneously, and connections between said units whereby said electromotive forces are merged.

2. Ignition apparatus, comprising, two magnetic circuits, a common source of flux therefor, a generating winding for each circuit, reciprocable armature flux changing

means forming part of said circuits and operable on each stroke to vary the reluctance of each circuit, controlling means to time the production of the electromotive forces in said windings one with the other so that two intermittent electromotive forces are produced simultaneously in the two windings on each stroke of said reciprocable means, and connections between said windings whereby 10 said electromotive forces are merged.

3. Ignition apparatus, comprising, two magnetic circuits, a common source of flux therefor, a generating winding for each circuit, reciprocable armature flux changing 15 means forming part of said circuits and operable on each stroke to vary the reluctance of each circuit, and controlling means to time the production of the electromotive forces in said windings one with the other so that two intermittent electromotive forces are produced simultaneously in the two windings on each stroke of said reciprocable means.

4. Ignition apparatus, comprising, two magnetic circuits each having a set of poles, 25 a generating winding associated with each circuit, a reciprocable armature for each circuit to periodically connect and disconnect its set of poles, means for moving first one and then the other of said armatures away 30 from its poles, whereby when the reluctance of one circuit is at a maximum that of the other circuit is at a minimum, controlling means for causing the flux change in each circuit on each stroke of each armature to 35 result in an intermittent electromotive force and for timing the intermittent electromotive forces so that as one is produced in one winding during the flight of its armature away from the poles another is simultaneously produced in the other winding while 40 its armature is on the poles, and connections between said windings whereby said simultaneously produced electromotive forces are merged.

5. Ignition apparatus, comprising, two magnetic circuits each having a set of poles, a generating winding for each circuit, a choke winding for each circuit arranged in an electrical circuit which can be opened 50 and closed, reciprocable armature means cooperating with said sets of poles to vary the reluctance of said magnetic circuits, means for simultaneously opening and for subsequently simultaneously closing each choke winding circuit twice during each reciprocation of said armature means and arranged to open said choke winding circuits while the reluctance of the magnetic circuit of one is substantially at a minimum and while the 55 reluctance of the other is substantially at a maximum, and connections between said generating windings for merging the electromotive forces thus simultaneously produced.

6. Ignition apparatus, comprising, two

magnetic circuits each having a set of poles, a generating winding for each circuit, a choke winding for each circuit arranged in parallel in an electrical circuit which can be opened and closed, reciprocable armature 70 means cooperating with said sets of poles to vary the reluctance of said magnetic circuits, means for simultaneously opening and for subsequently simultaneously closing each choke winding circuit twice during each reciprocation of said armature means, and connections between said generating windings for merging the electromotive forces thus simultaneously produced.

7. Ignition apparatus, comprising, two magnetic circuits each having a set of poles, a generating winding for each circuit, a choke winding for each circuit arranged in parallel in an electrical circuit which can be opened and closed, reciprocable armature 80 means cooperating with said sets of poles to vary the reluctance of said magnetic circuits, means for simultaneously opening and for subsequently simultaneously closing each choke winding circuit twice during each reciprocation of said armature means and arranged to open said choke winding circuits while the reluctance of the magnetic circuit of one is substantially at a minimum and while the reluctance of the other is substantially at a maximum, and connections between 85 said generating windings for merging the electromotive forces thus simultaneously produced.

8. Ignition apparatus, comprising, two magnetic circuits each having a set of poles, a generating winding for each circuit, a choke winding for each circuit arranged in an electrical circuit which can be opened and closed, reciprocable armature means 90 cooperating with said sets of poles to vary the reluctance of said magnetic circuits, means for simultaneously opening and for subsequently simultaneously closing each choke winding circuit twice during each reciprocation of said armature means and arranged to open said choke winding circuits while the reluctance of the magnetic circuit of one is substantially at a minimum and while the reluctance of the other is substantially at a maximum, and connections between 95 said generating windings for merging the electromotive forces thus simultaneously produced.

9. Ignition apparatus, comprising, two 100 magnetic circuits each having a set of poles, a generating winding for each circuit, a choke winding for each circuit arranged in an electrical circuit which can be opened and closed, reciprocable armature means 105 cooperating with said sets of poles to vary the reluctance of said magnetic circuits, means for simultaneously opening and for subsequently simultaneously closing each choke winding circuit twice during each reciprocation of said armature means, said generating windings being connected in series 110 whereby the electromotive forces simultaneously produced in each are added.

9. Ignition apparatus, comprising, two 115 magnetic circuits each having a set of poles, a generating winding for each circuit, a choke winding for each circuit arranged in an electrical circuit which can be opened and closed, reciprocable armature means 120 cooperating with said sets of poles to vary the reluctance of said magnetic circuits, means for simultaneously opening and for subsequently simultaneously closing each choke winding circuit twice during each reciprocation of said armature means and arranged to open said choke winding circuits while the reluctance of the magnetic circuit of one is substantially at a minimum and while the 125 reluctance of the other is substantially at a maximum, and connections between said generating windings for merging the electromotive forces thus simultaneously produced.

maximum, said generating windings being connected in series whereby the electromotive forces simultaneously produced in each are added.

10. Ignition apparatus, comprising, two magnetic circuits each having a set of poles, a generating winding and a choke winding associated with each circuit, a reciprocable armature for each circuit to periodically connect and disconnect its set of poles, two sets of cooperating and relatively movable breaker points, connected for operation one to each armature and separable by and during the flight of its armature away from its poles, an electrical circuit which includes said choke windings and said sets of breaker points, the latter connected in series so that the opening of either set will open the circuit of said choke windings, means for moving first one and then the other armature away from its poles, and connections between said generating windings for merging the currents produced therein.

11. Ignition apparatus, comprising, two generating units each adapted intermittently to produce an electromotive force, reciprocable armature means for alternately changing the flux in said units, and for decreasing the flux in one while the flux in the other is increased, means controlling the time of production of electromotive force in each unit on each stroke of said reciprocable means, said controlling means arranged to cause the electromotive force produced in one unit on a decrease of flux to occur at the same time that an electromotive force is produced in the other unit by an increase in flux, and connections between said units whereby the electromotive forces simultaneously produced are merged.

12. In a magneto, having two magnetic circuits including two sets of magnetic poles, reciprocable means forming part of said circuits for connecting first one and then the other of said sets of poles, a normally short circuited choke winding for each magnetic circuit capable of being periodically opened to release its magnetic circuit for a flux change, a generating winding for each circuit, means for simultaneously opening both said choke windings whenever either magnetic circuit is broken by said reciprocable means sufficiently to establish an air gap of predetermined degree therein, and connections between said generating windings for merging the currents generated by the simultaneous flux changes in both magnetic circuits.

13. In a magneto, having two magnetic circuits including two sets of magnetic poles, a choke winding and a generating winding associated with each magnetic circuit, reciprocable means forming part of said circuits and movable toward and away from each set of poles, said means arranged to increase

the reluctance of one circuit while the reluctance of the other is substantially at a minimum and vice versa, controlling means in circuit with said choke windings and normally maintaining the same short circuited to restrain flux change in the magnetic circuits, means operable as the reluctance in each circuit is increased to a predetermined degree to operate said controlling means and simultaneously open the choke windings and release both magnetic circuits for a flux change, whereby the flux builds up in one circuit and dies out in the other, and connections between said generating windings to merge the currents thus simultaneously produced in each.

14. In a magneto, having two sets of magnetic poles arranged in spaced relation, an armature for each set of poles and movable toward and away from the same, a common member to which both said armatures are connected for independent pivotal movement, and means for moving said armatures.

15. In a magneto having two sets of magnetic poles arranged in spaced relation, an armature for each set of poles and movable toward and away from the same, a common member disposed in a plane between said sets of poles to which both said armatures are connected for independent pivotal movement, and means for moving said armatures.

16. In a magneto, two parallel pairs of cores, a supporting frame therefor, a common source of flux connecting the cores of each pair at one end, an armature for each pair of cores cooperating with the other ends thereof and movable toward and away from the same, a common member arranged between the armatures to which each is connected for independent swinging movement, and means for operating said armatures.

17. In a magneto, two parallel pairs of cores, a supporting frame therefor, a common source of flux connecting the cores of each pair at one end, an armature for each pair of cores cooperating with the other ends thereof and movable toward and away from the same, a common member arranged between the armatures to which each is connected for independent swinging movement, and a common drive shaft disposed in a plane between said cores for operating said armatures.

18. In a magneto having two sets of magnetic poles arranged in spaced relation, an armature for each set of poles and mounted for movement toward and away from the same, means for supporting said armatures for said movement, and a common drive shaft for operating said armatures arranged in a plane between said sets of poles.

19. In combination, two magneto units, each of the type wherein a reciprocating armature moves into contact with the poles of a magnetic circuit while the circuit of the

choke associated with said magnetic circuit is closed, means for operating first one and then the other of said armatures so that one magnetic circuit is open at a time when the other is closed, two interrupters one operated by each armature and each operable during the downthrow of its armature to open the circuit of the choke winding associated with that magnetic circuit which said 10 armature controls, and connections whereby said opening of said choke winding circuit serves also to open the circuit of the other choke winding associated with the other magnetic circuit at a time when said circuit 15 is closed.

20. Ignition apparatus, comprising, two magnetic circuits, a generating winding for each circuit, reciprocable armature flux changing means forming part of said circuits and operable on each stroke to vary the reluctance of each circuit, and controlling means to time the production of the electro-motive forces in said windings one with the other so that two intermittent electromotive forces are produced simultaneously in the 25 two windings on each stroke of said reciprocable means.

In testimony whereof I have affixed my signature.

PHELPS BROWN.
